[57] CLAIM

The ornamental design for an actuator handle for pressure selecting valve, as shown.

DESCRIPTION

FIG. 1 is a front elevational view of an actuator handle for a pressure selecting valve showing my new design;
FIG. 2 is a top plan view thereof;
FIG. 3 is a bottom plan view thereof;
FIG. 4 is a right end elevational view thereof;
FIG. 5 is a rear elevational view thereof; and
FIG. 6 is a left end elevational view thereof.
